GEORGE T. WALKER, OF MILWAUKEE, WISCONSIN.

APPARATUS FOR CRYSTALLIZING LIQUIDS.

Application filed November 28, 1921. Serial No. 518,341.

In a great many chemical processes, a hot saturated solution of a compound is produced. This compound can be secured in a relatively pure form by cooling the solution. This cooling was formerly effected by allowing the solution to stand in large tanks or vats where cooling was spontaneous. This method gave large crystals and generally, they united in large masses which 10 adhered very firmly to the walls and bottom of the tank. A great deal of manual labor was required for the removal of the product, cooling was slow and dependent on the temperature of the air. This very simple process when applied on a large scale resulted in a high labor cost, and a heavy investment for tanks and buildings. The product had to be ground or pulverized if large lumps 15 were not desirable and it was subject to various forms of contamination during handling. It was found that the process could be improved by stirring the solution from time to time and the use of a jacketed tank which was water-cooled would hasten 20 the rate of cooling provided some means was provided to keep the cooling surface clear from the layer of crystals which tended to form on it.

In the effort to apply the above principles three styles of mechanical crystallizers were produced: The so-called Buffalo crystallizer which was simply a large water-jacketed saucer with a vertical shaft bearing two plows which scraped the bottom and 30 sides as they revolved. Another arrangement comprised a tank of approximately equal depth and diameter provided with coils for the cooling medium and a rapidly revolving propeller or stirrer which kept the 35 surfaces of the coils relatively clean because of the scouring action of the rapidly whirling liquid and crystals. The third commercial device was the Bach crystallizer which was a large horizontal jacketed cylinder provided with slowly moving scrapers to 40 remove the crystals from the inner surface of the cylinder.

While each of these types has been used considerably, they all required considerable attention and were very wasteful of water if it were necessary to cool the liquid to a temperature near that of the cooling water. Furthermore, in these devices, the wastage of cooling water was excessive because during the latter stages of cooling each batch, the

cooling water running from the crystallizer was practically as cold as when it entered.

In many processes, the final temperature of the cooled liquid must be closely controlled in order to avoid contamination of the product by crystallization of some form of impurity which would separate when the temperature was carried too low. To avoid this, when using batch machines which produced only a small tonnage per unit, it was necessary to exercise most careful control of the cooling.

The main object of the present invention is to provide a machine for the above purposes which is economical in the use of cooling water since the cold water cools the cold liquid and as it progresses through the machine is continually cooling warmer liquid; requires only a small amount of power; requires practically no labor or attention; is self-discharging; occupies a minimum of floor space; is cheaply constructed; can be adjusted to produce crystals of uniform size; is readily accessible at all times and at all points; can be easily regulated to produce a continuous discharge at a constant temperature and produces practically pure crystals from an impure liquid which are much less fragile than those produced by other apparatus or methods, and therefore, produce less dust when handled.

Still another object of this invention resides in the novel process of producing crystals of large and more uniform size.

These and other objects will in part be obvious and will in part be hereinafter more fully disclosed.

The one form of apparatus disclosed in this application comprises broadly a chamber to receive a heated liquid and a novel water jacket through which water is run to cool the liquid in the chamber. Preferably, the heated liquid is introduced within the chamber at one end thereof and is slowly impelled toward its outlet adjacent the other end thereof, while the cooling water travels through the water jacket as a counter-current, that is, the cool water is introduced within the water jacket adjacent the outlet of the heated liquid from the chamber, so that the discharging liquid is subject to the influence of the entrant relatively cool water.

The apparatus shown in the accompanying drawings is that of a present commercial

embodiment of the invention adapted for employment as a counter-current crystallizer. The heated crystalloidal liquid is introduced within the chamber at one end and 5 discharged at the other end, while the cooling water under suitable head enters the water jacket adjacent the discharge end of the chamber and has its outlet at the intake end of the chamber. The crystalloidal heated, liquid is slowly moved through the 10 open-topped chamber by either the natural inflow and discharge of the liquid or by means of a suitable impeller such as a modified form of screw conveyer comprising, as 15 here shown, a rotatable shaft extending through the chamber and having a ribbon thereon which makes less than a complete turn about the working portion of the relatively long shaft. A crystallizer of this 20 present type is preferably about forty feet in length and the shaft is rotated about one revolution per minute in order that the heated liquid may be exposed to water of seasonal temperature sufficiently long to 25 precipitate the crystals for subsequent removal.

In the accompanying drawings, there has been disclosed a structure designed to carry out the objects of the invention, but it is to 30 be understood that the invention is not confined to the exact features shown, as various changes may be made within the scope of the claims which follow.

In the drawings:

35 Figure 1 is a longitudinal median sectional view of the apparatus on the lines 1—1 of Figures 4 and 5;

Figure 2 is a plan view of the assembled apparatus;

40 Figure 3 is a longitudinally sectional view, on the lines 3—3 of Figures 4 and 5;

Figure 4 is a cross-sectional view on the line 4—4 of Figure 3;

45 Figure 5 is a similar view on the line 5—5 of Figure 3; and

Figure 6 is a sectional view of the liquid intake end of the apparatus.

In this selected embodiment of the invention here shown, there is provided a chamber substantially U-shaped in cross-section and thus open along the top. This chamber is preferably formed of sheet steel shaped to the desired form. Preferably the apparatus is made up of a plurality of similar chamber 55 units adapted for assembly into an elongated apparatus—as used at present the chamber is slightly less than forty feet long. In Figure 2, there are shown four such chamber units, 11, 12, 13 and 14 in assembled 60 terminally abutting relation. Adjacent units are held together with a water-tight connection by means of complementary angle irons 15 having portions respectively held by rivets 16 to each other and to the terminal portions of the abutting ends of adja-

cent chamber units. The semi-cylindrical or U-shape is employed because it is readily accessible at any point and at any stage of the operation. For this reason it is much easier to start it again if failure of power 70 results in a shut-down. These advantages are lacking in the cylindrical machine.

The elongated chamber of the assembled apparatus is provided with an intake connection 17 adjacent one end of the chamber 75 by means of which the heated liquid may be introduced within the open-topped chamber and with a discharge connection 18 adjacent the opposite end of the chamber. Means are provided within the chamber to impel 80 the heated liquid. A shaft 19 extends longitudinally through the chamber and is provided with gland bearings 21 at each end of the chamber, as the shaft, in this embodiment of the apparatus, is long, it is desirable to provide intermediate bearings therefor. Bearings 22 are integrally depended from hangers 23 carried by cross-arms 24 mounted transversely upon the longitudinal edges of the two chamber sides. The 85 hangers are secured to the cross-arms 24 by rivets 25 and the cross-arms are in turn held to the chamber sides by means of the angle plates 26 riveted both to the sides of the chamber and to the terminal portions of the 90 cross-arms as shown in Figures 4 and 5. An elongated or ribbon-like blade is substantially spirally carried by the shaft 19. This blade is preferably not continuous in order that the intermediate shaft bearings 22 may 95 be employed. Hence, the blade is formed of a plurality of complementary sections 27. The blade sections 27 are carried by spokes 29 suitably secured to the shaft at spaced intervals. As is shown in Figure 2, this 100 blade is substantially spirally disposed about the shaft 19 but preferably does not effect a complete turn about the shaft in order that the heated liquid may be sluggishly impelled by the slow rotation of the shaft 19 from any 105 power source not necessary to be shown. The heated liquid may be introduced within the chamber by way of the intake connection 17 indicated at the right end of Figure 2 and as shown in Figure 6. This end may 110 be termed for sake of clarity, as the front end of the apparatus, while the opposite end having the liquid discharge connection 18, may be termed the rear end. The liquid is 115 very slowly moved by the shaft blade toward the rear end of the machine and during its motion, the liquid is gradually cooled by water running through the surrounding water jacket in an opposite direction.

The water jacket is provided with means 120 for causing the current of water to pursue a tortuous course in its transit of the chamber exterior. Similarly to the chamber, the water jacketing is effected by a plurality 125 of units, each being secured to a chamber 130

unit and a pipe connection being provided successively to connect the water jacket units. Each water jacket unit is formed by a casing 31 comprising a piece of sheet metal shaped to extend about its supplementary chamber unit in spaced relation thereto. The two longitudinal edge portions 32 of the casing are both inwardly offset and are held tightly against the adjacent 10 outer surface of the chamber unit by means of the depending sections of the riveted angle plates 26. A water-tight closure of the top of the water jacket is thereby effected. The ends of the water jacket casings 15 are closed by means of the U-shaped bars 33, the end portions of the casing extending over the outer faces of the bars and rivets being passed through the casing, bars and chamber units. The cooling water is supplied 20 under sufficient head to the water inlet connection 34 and thus enters the rear unit 14 and thereafter is successively passed to the adjacent jacket units by means of pipe connections 35, and finally is ported through 25 the outlet connection 36 at the front end of the apparatus.

The water is caused to follow a tortuous course from side to side of the chamber by means of baffle plates 37. These baffle plates 30 are elongated metallic strips with a narrow marginally offset flange 38 (see Figure 1) whereby each may be suitably secured to the inner face of the adjacent casing unit. As is indicated in Figure 3, one leg of each 35 of these U-shaped baffle plates 37 is shorter than the other, and these plates are alternately disposed in spaced relation in each water jacket unit. Thus, the moving water passes over the short leg of one baffle plate 40 at one side of the chamber unit and must then travel to the other side of the chamber unit to the next short leg, etc. Such baffled course of the cooling water causes a more effective and uniform cooling of the chamber and therefore of the heated liquid therein. The jacket as above described, is so constructed that the cooling medium can be distributed in a thin layer in order to obtain a high velocity of flow with a relatively 45 small amount of water. High velocity causes an increased heat transmission. The baffles also serve the same purpose as they cause the cooling medium to follow a long route and therefore to travel at a high rate 50 of speed. Transverse baffles are used in preference to longitudinal baffles or partitions in order that the water may be continuously warmed as it passes through the machine and yet always be cooler than the 55 liquid to be cooled at any point. In the case of longitudinal baffles or partition as the water was warmed it would pass alternately from the warm to the cool end of the crystallizer and therefore will be warmer than 60 the liquid to be cooled at the cool end of

the machine unless an unnecessarily large volume of water is used. Such baffling is not based on the true counter-current principle. While the jacket in my machine causes a high velocity of the cooling medium 70 the passages are large and the use of large connections from section to section allow the use of a large volume of water and therefore the use of very long units for large capacity with minimum attendance. 75

In the present operation of this apparatus in connection with heated crystalloid liquid, such liquid is supplied to the chamber by means of the intake connection 17 so that the chamber is filled to the level of 80 the discharge connection 18. The water runs from the rear end to the front end through the water jacketing. The shaft 19 is slowly revolved so that the liquid is very gradually moved toward the rear of the chamber while 85 any crystals formed by the cooling of the liquid are likewise moved toward the rear end of the apparatus. The cooled liquid is slowly discharged through the discharge connection 18 carrying with it any crystals 90 which are capable of floating in the liquid whereupon the crystals are subsequently recovered, or the crystals may be precipitated to the bottom of the casing and slowly gathered at the rear end through action of 95 the impeller whereat they may be recovered from time to time.

It will be noted that a spiral of extremely long pitch is used. A standard spiral of a pitch about equal to the diameter merely 100 pushes the crystals forward without lifting them so that they will not be discharged unless there is an opening in or near the bottom. Such an opening would make it impossible to fill the machine with liquid and 105 therefore only a small portion of the cooling surface would be actually available.

The long spiral has a lifting effect so that the crystals are constantly and repeatedly lifted and allowed to fall through the liquid. 110 During this process growth occurs so that coarse crystals can be produced although the rate of stirring is relatively rapid. This lifting and rapid stirring keeps the cooling surface clean and prevents insulation although 115 there is no contact of metal with metal, which would cause a great increase in the power required and result in contamination of the crystals by the particles of metal removed by such contact. To keep such contact would 120 also require frequent adjustment and severe wear. This lifting effect also furnishes a means of discharging the crystals from the machine so that it can be operated continuously. When first filled very few crystals 125 are discharged but they are gradually carried forward by the spiral and the flow of the liquid which is being constantly introduced at the hot end. In time the density of the mixture of crystals and liquid at 130

the cool end becomes sufficient to prevent rapid sinking of the crystals as they are lifted by each blade of the spiral, as each blade rises it lifts a mass of crystals to the discharge opening and some of them are carried out by the outflowing liquor. This discharge is perfectly automatic without the aid of any special mechanism.

By the above means the crystals are being constantly dropped through a saturated solution which is just ready to deposit a small portion of the dissolved salt since it is being constantly cooled. This is deposited on the crystals which have already been formed instead of forming nuclei and causing the production of a great many fine crystals. It is a rather common experience in operating batch crystallizers that crystals do not commence to form gradually but the liquid becomes slightly super-cooled and suddenly a great number of extremely fine crystals form. Such batches are generally decidedly different in appearance from normal batches.

I claim as my invention:

1. In an apparatus for crystallizing liquids, the combination of an elongated chamber, an inlet adjacent one end of the chamber whereby a heated liquid may be introduced into said chamber, an outlet for the liquid adjacent the top opposite end of the chamber whereby to maintain a level of liquid therein, a water jacket therefor adapted to have cooling water run therethrough whereby the liquid within the chamber may be cooled, an impeller in said chamber actuable to cause the liquid to be impelled from the inlet toward the outlet.

2. In a crystallizer, the combination of a tank, means for introducing heated crystalloidal solution into said tank at one end thereof, a liquid discharge arranged substantially at the top opposite end of said tank for overflow discharge whereby to maintain said tank substantially full, means for cooling said liquid in its passage toward said discharge whereby to cause said liquid to form crystals, and means for lifting said

crystals and dropping them through said liquid to assist in their growth.

3. In a crystallizer, the combination of a tank, means for introducing heated crystalloidal solution into said tank at one end thereof, a liquid discharge arranged substantially at the top opposite end of said tank for overflow discharge whereby to maintain said tank substantially full, means for cooling said liquid in its passage toward said discharge whereby to cause said liquid to form crystals, and means for lifting said crystals and dropping them through said liquid to assist in their growth, and for lifting such crystals to said discharge whereby they may be carried away with the outflowing liquid.

4. A crystallizer comprising a tank having an inlet and an outlet arranged to permit the flow of heated crystalloidal solution through said tank and to maintain a level of liquid therein, means for progressively cooling said solution during its flow whereby to cause the saturation of said solution and the formation of crystals, and means for lifting said crystals and dropping them through the liquid to assist in their formation, said means serving to advance said crystals through said tank and to lift and present them to the outlet for discharge therefrom with the outflowing liquid.

5. A crystallizer comprising a relatively long tank having an inlet and an outlet at substantially opposite ends thereof for the introduction and discharge of heated crystalloidal solution, and to maintain a level of liquid therein, means for progressively cooling said solution, a slowly rotating spiral arranged within and extending substantially the length of said tank and having an extremely long pitch, and arranged to move said crystals upwardly and toward the discharge of said tank.

In witness whereof, I have hereunto set my hand this 25th day of November, 1921.

GEORGE T. WALKER.
